DIRECTION SIGNAL

Filed May 19, 1926

UNITED STATES PATENT OFFICE.

LOUIS E. H. HUBER, OF PHOENIX, ARIZONA.

DIRECTION SIGNAL.

Application filed May 19, 1926. Serial No. 110,208.

My invention relates to direction signals for motor vehicles, and the purpose of my invention is the provision of a manually operable signal more particularly designed for use in connection with the windows of closed motor vehicle bodies and capable of being applied to a window glass in such manner as to permit complete closing of the window and the operation of the signal to give its several indications from a point interiorly of the vehicle and while the window is completely or partly closed.

It is also a purpose of my invention to provide a direction signal of the above described character which is extremely simple, inexpensive and durable in construction and which is capable of being quickly applied to or removed from the window.

I will describe only one form of direction signal embodying my invention and will then point out the novel features thereof in claims.

In the accompanying drawing,

Figure 1 is a view showing in vertical section a vehicle window in completely closed position with one form of direction signal embodying my invention in applied position thereto and with a portion of the latter in section;

Figure 2 is a view similar to Figure 1 showing the semaphore arm of the signal in one of its indicating positions;

Figure 3 is a fragmentary view showing in front elevation the direction signal in applied position to the window;

Figures 4 and 5 are sectional views taken on the line 4-4 and 5-5, respectively, of Figures 1 and 2, respectively.

Referring specifically to the drawings, my invention, in its present embodiment, comprises a bracket formed of relatively thin material, such as metal or the like and of substantially U-shaped form, so as to snugly embrace the opposite sides and upper edge of a window 15. The bracket consists of a relatively short arm 16 disposed at the inner side of the window and the relatively long arm 17 disposed at the outer side of the window, with a portion 18 connecting the two arms at their upper ends and lying contiguous to the upper edge of the window.

Formed integral with the bracket is a conduit 19 also of U form and relatively flat as shown in Figure 3, so as to be capable of being received within the groove 20 of the upper edge of the window frame and yet

permit the window to occupy a completely closed position. The inner side of the conduit 19 terminates at the lower end of the arm 16, the arm and conduit at this point being flared outwardly from the window as indicated at 21, for a purpose to be described hereinafter. The other arm of the conduit terminates short of the bracket arm 17 and adjacent to this arm is a rounded ear 65 or projection 22 formed on or secured to the arm 17. A semaphore arm is pivoted on the ear 22 at the point indicated at 23, and this semaphore arm is made up of a master blade 24 of U-shaped form in cross section 70 so as to provide a housing in which a plurality of blades 25 are adapted to be nested when the semaphore arm occupies the normal position shown in Figure 1. The several blades 25 are pivoted at a common point 26 to the master blade 24, and at their lower or outer ends they are operatively connected to each other and to the master blade in a manner to permit occupying the extended or fan-shaped position shown in Figure 2 when 75 the master arm is moved to any one of its several indicating positions. Any suitable means may be employed to secure this result, but in the present instance I have shown the outer ends of the master blade and certain 80 of the other blades formed with in-turned lips 27 which form grooves in which pins 28 slide. As shown in Figure 5, the lower ends of the grooves are closed by in-turning the lips as indicated at 29, so as to limit the 85 downward movement of the pins in the grooves and to thereby cause the blades to occupy the fan-shaped positions when the master blade is elevated. This connection between the blades also permits the blades 90 95 to nest within the master blade when the latter is moved to the position shown in Figure 1.

The semaphore arm is capable of being moved from the normal position shown in Figure 1 to any one of the three indicating positions by means of a cable, cord or the like 30 connected to the master blade 24 at the point indicated at 31 and extended over the ear 22 and through the conduit 19 with 100 its inner end depending from the conduit at the inner side of the window and provided with a handle 32. A spring 33 is connected to an out-struck lug 34 formed on the arm 17 and to the master blade 24 so as 105 to yieldably urge the semaphore arm to the normal position shown in Figure 1 and to 110

thereby prevent rattling of the semaphore arm against the window.

In the operation of the signal, the handle 32 is within convenient reach of the driver so that by pulling downwardly on the cable 30 the master blade 24 will be elevated to any position desired and against the action of the spring 33, the blades 25 under the elevating movement of the master blade automatically moving to the fan-shaped position shown in Figure 2. When the cable 30 is released, the spring 33 will function to return the semaphore arm to normal position and during such return the blades 25 are nested within the master blade.

An important feature of my invention is the provision of a mounting for the semaphore arm on a motor vehicle window which permits of the complete closing of the window and the operation of the semaphore arm from a point at the inner side of the window so that in inclement weather the driver of the vehicle may completely close the window and still operate his signal. When it is desired not to use the signal, it may be readily removed from the window and as easily applied when desiring to use the same.

Although I have herein shown and described only one form of direction signal embodying my invention, it is to be understood that various changes and modifications may be made therein without departing from the spirit of the invention and the spirit and scope of the appended claims.

I claim as my invention:

1. A direction signal comprising a U-shaped bracket, a U-shaped conduit on the bracket, a rounded projection on the bracket, a semaphore arm pivoted on the projection, and a cable connected to the arm at a point below the pivot thereof so as to engage said projection, said cable being trained through the conduit.

2. A direction signal comprising a U-shaped bracket, a U-shaped conduit on the bracket, a rounded projection on the bracket,

a semaphore arm including a master blade pivoted on the projection, and a plurality of other blades pivoted on the master blade to occupy folded or extended positions, a spring for urging the master blade toward the bracket so that the other blades will be folded within the master blade, and a cable connected to the master blade at a point below the pivot of the latter so as to engage said projection, said cable being trained through the conduit and freely movable therein to permit actuation of the semaphore arm.

3. In a direction signal, a bracket of substantially U shaped form adapted to snugly embrace the opposite sides and upper edge of a vehicle window and including relatively short and long arms adapted to be disposed at the inner and outer sides of the window respectively and connected at their upper ends by a transverse portion adapted to lie contiguous to the upper edge of the window so as to permit closing of the latter, the short arm, transverse portion, and upper portion of the long arm being hollow to provide a flat conduit flared outwardly at its ends, the remaining portion of the long arm being flat and provided below the end of its conduit portion with a substantially semi-circular flat projection upon which is adapted to be pivotally mounted the master blade of a semaphore arm having a plurality of pivotally mounted blades capable of being extended to assume a fan shaped position when the master blade is elevated, a flexible cable adapted to be connected at one end to the master blade at a point below its mounting on the projection, said cable trained over the projection and extending through the conduit, a handle on the cable for actuating the latter, and a spring connected to the long arm and adapted to be connected to the master blade for normally urging the semaphore arm into engagement with the last mentioned arm.

LOUIS E. H. HUBER.
